UNITED STATES PATENT OFFICE

2,130,917

DISPLAY SIGN

Joseph E. Bielski, Oak Park, Ill.

Application April 7, 1938, Serial No. 200,593

12 Claims. (Cl. 40—40)

This invention relates to display signs, and more particularly to signs in which advertising matter is presented to view in changing or dissolving effect, that is, moving before the vision of a person observing the same, successively in an obverse direction to the direction of reading or alternating view in either direction, thus providing an attractive and inexpensive medium of bringing advertising or slogans for products or

wares before the purchasing public.

The invention further contemplates an illuminated display or sign device in the form of a heat lamp embodying an opaque casing adapted to be moved or rotated about a lamp bulb and having one or more sides with an opening therein and a corrugated or similar panel set behind the opening with a plurality of display characters thereon visible at different angles, thus providing an attractive device with a constant change of characters or reading matter.

Another object of the invention is to provide a novel display panel and arrangement of display matter thereon in conjunction with the moving casing or wall and an opening through which the panel is displayed in front of an illuminating means, if desired.

Other objects and advantages will appear and be brought out more fully in the following specification, wherein:

Fig. 1 is an elevation of a display sign associated with a heat lamp;

Fig. 2 is a plan view;

Fig. 3 is a sectional view taken on the line 3—3 of Fig. 1;

Fig. 4 is a horizontal sectional view taken on the line 4—4 of Fig. 1 with parts in elevation;

Fig. 5 is an enlarged fragmentary sectional view taken along the section line 5—5 of Fig. 2;

Fig. 6 is an enlarged detailed sectional view taken on the line 6—6 of Fig. 3;

Fig. 7 is an enlarged view of the casing of the display sign;

Fig. 8 is an enlarged fragmentary view of one of the panels in extended or stretched out position; and

Fig. 9 is an enlarged fragmentary sectional view showing a modification of the panel construction.

Referring more particularly to the drawings, 10 is a lamp stand having a socket 11 at the upper end from which extends a cord 12 having a plug 13 adapted to be connected to a wall socket for supplying current, the lamp being controlled by a switch 14. A bulb 15 fits in the socket 11 and supports a spring wire clamp 16 having a pointed bearing 17 extending upwardly

for movably or rotatably supporting a heat lamp 18. This heat lamp may be of any preferred design but is shown as embodying a transparent chamber or cylinder 19 of celluloid or other transparency reinforced by bands 20 at the upper and lower ends thereof and held by staples or other fasteners 21, certain of which pass through overlapping portions 22 of the transparent cylinder and the bands.

The cylinder 19 is arranged within a casing in the form of a shade 23 of opaque material such as cardboard suitably ornamented externally to render the same attractive in appearance. As illustrated, this casing is triangular in cross-section, but may be any suitable shape, and instead of being polysided, may simply be a wall suitably arranged in front of a lamp or other illuminating means and arranged to completely or partially revolve or rotate about the same or have other form of movement imparted thereto such as oscillatory movement or otherwise. The shade 23 may be formed of a strip and the ends thereof may be overlapped and glued or otherwise fastened as at 23a at one corner or otherwise.

The shade or casing 23 is open at the bottom so as to fit over the lamp bulb and is closed near the top by a wall 24 shown having edge portions 25 folded upwardly against the inner faces of the walls or sides of the shade and suitably glued or otherwise fastened thereto. The top of the cylinder 19 is fastened beneath the cover or top wall 24 at an opening 26 provided therein as by means of angular pieces 27 glued or otherwise secured to the underface of the top wall 24 and between the cylinder wall 19 and the upper band 20 so as to suspend the cylinder.

Over the opening 26 in the wall 24 is arranged a fan 28, certain blades of which have tongues 29 extended through slots in the top 24 and clinched, as particularly seen in Fig. 5. The fan 28 is preferably of metal and has a central opening 30 receiving a bulbous glass or other bearing 31 with a spherical closed upper end and a flange 32 at the bottom disposed against the bottom face of the central portion of the fan and held in position by a clip 33 above said central portion. This bearing is designed to fit over the pin bearing 17 so that the heat from the bulb and the heat waves impinging upon the blades 28 will cause the shade to rotate in a given direction according to the angular position of the blades.

Each side of the shade or casing 23 is provided with an opening 34 which, while shown oval, may be of other desired geometrical outline. Arranged in back of each opening is a panel 35 of

paper or other suitable translucent material shown corrugated and suitably glued or otherwise fastened to the inner faces of the sides of the shade at the ends 36 as well as at the top and bottom edges so as to entirely cover the opening 34 and overlie the edges thereof. The alternate or opposed faces of the corrugations are printed or otherwise produced with suitable sets of characters 37 and 38, parts of each character 10 being printed or otherwise produced upon alternate or staggered walls of the corrugations facing in the same direction so that when viewed at different angles from one direction, one of the characters will be visible and when viewed at different angles from the opposite direction, the other characters will be visible. These panels 15 may be suitably ornamented or colored and the printing or characters are preferably made of contrasting colors so as to produce an attractive 20 medium for advertising products or wares of certain manufacturers visible to passersby when the lamp is placed in a conspicuous location. While the characters will be visible in daylight without illumination, they will be rendered more attractive and visible at night by the illumination of the panels, and the projection of light through the same from the lamp or electric light bulb 15 constituting the illuminating means in the embodiment shown.

30 It may also be mentioned that while the imprinting of the characters on the panels and the corrugations thereof may be effected in any suitable manner and sequence, these panels are preferably first printed with the characters and 35 then corrugated, the parts of at least two different characters being printed upon alternate divisions 39 and 40 of the panel running vertically and representing the opposed faces of the corrugations facing in opposite directions or in angular 40 relation to each other at any desired degree of angle, and then corrugated along the lines of the divisions between these corrugations, as will be more readily apparent from Fig. 8 of the drawings. This provides an effective and practical 45 method of producing the panels economically in quantities so that the advertising matter thereof may be changed as the occasion arises.

In Fig. 9 of the drawings, a modification is 50 shown in which instead of individual panels for each side of the shade or casing fastened at the margins thereof, a single strip may be employed for all three sides with intermediate portions 26a glued or otherwise secured to the corner or angular portions of the shade, so that a plurality 55 of panels together with the characters thereon may be produced at one time and then fastened in position over the openings, after corrugating. In either instance, it will be obvious that the primary embodiment of the invention comprises a 60 wall having an opening with a panel in the opening of corrugated or similar cross-section and bearing characters of contrasting design thereon in which divisional portions of the characters are produced upon spaced alternate or staggered divisions of the panel. Thus, when the panel is corrugated, the portions of the different characters facing in the same angular direction will be brought into alignment so as to appear continuous in formation and viewed with attractive effect at different angles so that one character may 65 be visible from one side and the other character from the other side while both characters will be visible in a direction normal to the plane of the panel and the wall on which it is mounted.

70 While a heat lamp will cause the shade to 75

rotate, and especially adverse to the direction of reading, it is to be understood that the panel may be moved in any other way or may have limited rotation or may be oscillated to render the different characters successively visible. This 5 provides an attractive display of advertising matter whereby said advertising matter or slogans pertaining to products may be brought before the purchasing public and, therefore, constitutes an inexpensive medium of advertising.

It is also to be understood, instead of sharp angular portions of the corrugations, as illustrated, the panel may be otherwise suitably corrugated in sinuous or wavy form with similar effect upon the display matter or characters thereon, 15 but in either case, the opposite sides or outer exposed folds or sides of the corrugations bearing parts of the advertising display will be divided and arranged upon alternate or staggered portions of the face of the panel to give the same 20 effect as heretofore described herein.

While I have illustrated and described the preferred form of construction for carrying my invention into effect, this is capable of variation and modification without departing from the spirit of 25 the invention. I, therefore, do not wish to be limited to the precise details of construction set forth, but desire to avail myself of such variations and modifications as come within the scope 30 of the appended claims.

Having thus described my invention, what I 35 claim as new and desire to secure by Letters Patent is:

1. In a display sign, a light impervious wall 35 with an opening and a corrugated panel adapted to pass light therethrough mounted over the opening, alternate corrugations having different characters thereon visible at different angles and both being visible intermediately and means to mount said panel to move to different angular 40 positions.

2. A display sign including an opaque wall with an opening and a panel to permit light to be emitted therethrough in back of the opening having corrugations with alternate obverse portions thereof produced with different characters successively visible in the direction of reading, said wall and panel being mounted to move to present the characters to view from different 50 directions.

3. A display sign including an opaque wall with an opening and a panel in back of the opening having corrugations with alternate portions thereof produced with different characters alternately viewed from different angles, said panel 55 being translucent and adapted to be illuminated from the back, and said panel being adapted to move so as to present the characters from different angles of view.

4. As an article of manufacture, a display sign panel produced with spaced alternate portions thereof having contrasting characters adapted to appear continuous when the panel is rotated and means mounting said panel to turn to present different views to the observer.

5. As an article of manufacture, a display sign panel produced with spaced alternate portions thereof having thereon different characters, and the panel being corrugated along lines constituting the divisions between said spaced alternate portions whereby the characters will appear continuous and presented to view simultaneously at an angle substantially normal to the panel and independently at opposite angles when the panel 70 75

is rotated, and means to move the panel to present the indicia to view from different angles.

6. In a display sign, a wall having an opening, a translucent corrugated panel behind the opening, illuminating means behind the panel, and characters produced upon the panel adapted to be viewed from different angles, each character having portions produced upon spaced alternate and different corrugations of the panel, said wall being mounted to turn and provide with means for driving the same and the panel for view in different directions.

7. As an article of manufacture, a corrugated sign panel of translucent material, and a plurality of characters arranged upon the panel, portions of the characters being alternately arranged upon spaced opposite faces of the corrugations to be viewed from different angles as continuous characters, and means mounting the panel to move so as to present the characters from a different angle of view.

8. In a display sign, a heat lamp having illuminating means, a shade adapted to rotate thereon and having sides with openings in front of the illuminating means, and panels over the openings through which light from the illuminating means is projected, said panels being corrugated and having characters produced upon faces of the corrugations so that different characters may be viewed from different angles and both visible from a position substantially normal to the planes of the panels.

9. In a display sign, a light excluding wall having an opening, a corrugated light emitting panel for the opening having display matter thereon independently visible at different angles, appearing continuously when viewed at an angle substantially normal to the panel, said wall be-

ing mounted to move in a circular path so as to present the indicia from a different angle of view.

10. As an article of manufacture, a panel with characters printed on spaced alternate parts 5 thereof and then corrugated so that all parts of each character will be read from the same angle, different characters from different angles and all characters at points in between said angles, and combined to form a continuous combined character free of breaks when viewed at an angle, said panel having means to mount the same to turn.

11. In a display sign, a movable opaque body constituting a display casing having an opening 15 with a translucent corrugated panel over the opening and bearing advertising matter upon the opposite sides of the corrugated faces thereof visible at different sides upon movement of the body at different angles means mounting the body 20 and panel to turn and means for turning the same.

12. In a display sign, a heat lamp including a transparent chamber having illuminating means, a casing open at the bottom to fit over the il- 25 luminating means and having a top with an opening over the top of the chamber, means to support the casing for rotation about the illuminating means, said casing having openings, and panels in back of the openings through which 30 light from the illuminating means is emitted, said panels being corrugated and having different characters produced upon opposite faces of the corrugations so that different characters may be viewed from opposite angles upon move- 35 ment of the casing and both visible between said angles.

JOSEPH E. BIELSKI.
